UNITED STATES PATENT OFFICE.

ARTHUR E. SMALL, OF CHICAGO, ILLINOIS, ASSIGNOR TO UNION METAL PRODUCTS COMPANY, OF CHICAGO, ILLINOIS, A CORPORATION OF DELAWARE.

METAL END STRUCTURE FOR RAILWAY CARS.

Original application filed October 19, 1922, Serial No. 595,634. Divided and this application filed January 3, 1927. Serial No. 158,595.

My invention relates to the construction of railway cars and more particularly to metal end structures or walls for railway cars made of one or more metallic plates or panels formed with integral reinforcing, stiffening and bracing embossments or corrugations. However, this device may be incorporated in the construction of car side walls, floors, roofs or doors used in connection with railway cars of various types.

It is well known that the end walls of railway cars are more likely to be broken or otherwise injured than the side walls. This is due to the inertia thrusts and pressures caused by the shifting of the cargoes when the train starts or stops. These thrusts may be local, tending to distort the end in some particular spot, as, for example, when a piece of piping or lumber shifts lengthwise imparting a blow against the end wall of the car; or there may be a general tendency to break out the end wall as a whole or tear it away from the framing. For the purpose, therefore, of greater strength and durability, car ends have been constructed of metal plates corrugated or formed with ribs to impart the desired strength, rigidity and resiliency.

One of the principal objects of my invention is to provide a corrugated metallic end structure for railway cars in which the corrugations have a configuration and arrangement that impart to the structure a maximum capacity for resisting cargo thrusts, both local and general, static or quiescent, and with sufficient resiliency to prevent permanent distortion due to the thrusts of the loads, with a minimum weight of metal. It is important that structures of this sort should be as light as is possible, consistent with strength and durability, both for reasons of economy in manufacturing cost and also to keep the weight of the car at a minimum.

A further object is to provide a corrugated metallic wall element that is practically possible to manufacture. A further object is to provide a metallic wall element with corrugations that resist to a greater degree torsional stresses, as well as brace the element and the car end against diagonal side thrusts or weaving.

Another object is to form a metallic plate with integral corrugations or ribs which im-

part to it a certain amount of strength and 55 rigidity to resist loads imposed thereon and to so form the ends of the corrugations or ribs as to provide a certain amount of resiliency to enable the plate to deflect and return to its normal position without appreciable 60 amount of permanent distortion.

Like characters of reference designate like parts.

The end wall structure shown in the above figures comprises a panel composed of a corrugated metal plate or plates.

Referring to Figs. 1 and 2. The corrugated plates 1, 2 and 3 extend across the car from side to side and are formed with integral flanges 4 along the vertical edges which overlap and are secured to the side walls 5 of the car by any suitable means.

The top edge of the upper plate is secured beneath the fascia boards 7 and the meeting edges of the plate overlap and are secured together by rows of rivets 8 and the lower edge of the lower plate is secured to the end sill 9. Nailing strips 10 are secured to the plates 1, 2 and 3 by bolts and lining 11 is secured to the nailing strips 10.

Figs. 3 and 4 show a modified form of the invention applied to a gondola type of car, wherein only one plate 12 is used to form the end panel which extends from side to side of the car and is provided along the vertical edges with flanges 13 which overlap and are secured to the side walls 14 by any suitable means. The top edge of the plate is secured to the top chord 15 by rivets 16, while the lower edge is secured by rivets 17 to the end sill 18.

While the corrugations are shown pressed outwardly, and in horizontal arrangement, it is understood that the corrugations may be pressed inwardly, or partially inwardly and partially outwardly, from the original plane of the plate or the corrugations may be placed in any position; for instance, vertically or diagonally. The plates or panels may be positioned vertically or horizontally and applied to any type of railway car.

Figs. 5 to 9 inclusive show the preferred form wherein the plate is provided with a plurality of parallel embossments, each embossment comprising a plurality of relatively shallow sinuous minor corrugations 20 formed therein which are spaced apart distances equal to their respective widths and the portion of the plate between adjacent minor corrugations is also sinuous so that these minor corrugations merge together to form a contiguous sinuous configuration symmetrical in cross section about a line midway between the outermost portions of these minor corrugations so that this line is the neutral axis of the section. Such a section is very resilient and has a spring like action under loads, and, furthermore, produces a very strong section for the amount of metal used. These minor

corrugations merge into the plane of the plate by means of terminal portions of any desired formation. A plurality (two or more) of such minor corrugations 20 merge together adjacent the middle of the plate 70 (or middle of the embossment comprising the minor and major corrugations) to form a lesser number of relatively deep corrugations 21 with flat apices 25 which are spaced apart distances equal to their respective widths and the part 26 of the plate 24 between these major corrugations is also flat, thus forming a configuration symmetrical in cross section about a line midway between the outermost portions of these major corrugations so that this line is the neutral axis of the section. Such a section is stronger and relatively rigid as compared with the section of the sinuous minor corrugations because more metal is positioned away from the neutral axis and the increased depth also increases the strength of the beam. By such an arrangement a corrugated metallic plate is provided which is relatively rigid adjacent the middle portion of the embossments and relatively resilient adjacent the opposite end portions of the embossments.

The secondary oppositely projecting rib or corrugation 22 formed by the merging of the two adjacent minor corrugations 20 is equal in width to the adjacent minor corrugations at 23 and decrease in width as the minor corrugations merge together to form the major corrugation 21. These secondary oppositely projecting ribs 22 also preferably decrease in depth so that any concentrated stretch of metal is eliminated where the minor corrugations merge together.

As the embossment increases in depth toward its middle portion, this secondary rib preferably decreases in depth proportionately so that the lengths of the center lines of the metal of all cross sections of the embossment are equal to each other.

I have designed my invention for use in steel plates so that when the section modulus of any section (normal to the corrugations) is multiplied by a constant fibre stress the result equals the bending moment of that section for either a load concentrated at the middle of the beam-corrugations or for a load equally distributed over the beam-corrugations, thus showing that I have not sacrificed any required strength at the ends 115 of the beams to obtain resiliency; in other words, by my construction I obtain a very strong beam which is also resiliency. The major corrugations are preferably wider than the minor corrugations.

These shallower and deeper corrugations may be positioned and dimensioned so that the length of the center line of the metal of a cross section of the shallower corrugations (see Fig. 9) is the same as the length of the 130

center line of the metal of a cross section of the deeper corrugations (see Fig. 7) and, furthermore, the corrugated plate may be so formed that the length of the center line of the metal of any cross section (for instance, as per Fig. 8) is equal to the length of the center line of the metal of any other cross section, that is, between the terminal portions. This is a material manufacturing advantage as it more evenly distributes the draw and stretch of the metal due to pressing the corrugations in the plate.

Figs. 10, 11 and 12 are detail enlargements of portions of the plate taken on lines 15 7, 8 and 9, respectively, of Fig. 5 showing the flat apex 25 of the major corrugation (Fig. 10) split or divided by the secondary corrugation 22 into two contiguous sinuous corrugations 20 (Fig. 12).

20 Figs. 13, 14 and 15 are detail enlargements of a modified form of corrugation similar to Figs. 10, 11 and 12, respectively, wherein the apex (29) of the major corrugation is arcuate.

25 Figs. 16 to 20 inclusive show a modification wherein the embossments have parallel sides.

Figs. 21 to 25 inclusive are similar to Figs. 5 to 9 inclusive except that they illustrate three minor corrugations merging into 30 a single major corrugation.

Figs. 26 to 30 inclusive show a modified form wherein the major corrugations 31 have arcuate or sinuous apices 30 and the 35 portion of the plate 31 between adjacent embossments is also arcuated or sinuous.

Plates provided with a plurality of contiguous narrow corrugations possess a considerable amount of elasticity and when 40 struck a blow deflect readily and regain their shape without distortion, whereas a plate provided with wide flat corrugations, though better able to carry quiescent loads, has not the resiliency of the former and is 45 more readily distorted when struck a blow.

It is, therefore, desirable to design a plate that possesses great strength to withstand the sudden impact load blows with sufficient resiliency to resist distortion.

50 The particular form and advantages of the terminations of the corrugations illustrated in Fig. 5 are not described or claimed specifically herein, but are described and claimed in my Patent No. 1,547,831 dated July 28, 1925, for corrugated wall elements.

This application is confined to the construction wherein the minor corrugations merge to form the major corrugations, while my application Serial No. 595,632, filed October 19, 1922, for corrugated metallic wall elements covers the construction wherein the major corrugation is split into two or more minor corrugations.

60 This is a division of my co-pending application Serial No. 595,634, filed October 65

19, 1922, as is also my application Serial No. 55,207, filed September 8, 1925.

I claim:

1. A metallic wall panel for railway cars having a reinforcement formed therein, 70 comprising a plurality of stiffening ribs which merge into each other to form a relatively wider stiffening rib adjacent the center of said reinforcement, the height of said reinforcement being greatest adjacent its 75 center and almost parallel to the first mentioned ribs.

2. A metallic plate wall element having a plurality of corrugations terminating within 80 said plate that merge into a lesser number of wider and deeper corrugations adjacent the center of said plate, the cross sectional area of said corrugated plate being equal anywhere between the planes where 85 said corrugations begin to terminate into the plane of said plate.

3. A metallic plate provided with a plurality of corrugations spaced apart distances substantially equal to their width, 90 said corrugations merging adjacent the middle of the plate into a lesser number of wider and deeper corrugations spaced apart distances substantially equal to their width.

4. A metallic plate provided with a plurality of corrugations merging adjacent the 95 middle of the plate into a lesser number of wider and deeper corrugations and almost parallel to the first mentioned corrugations.

5. A metallic plate provided with a plurality of corrugations spaced apart distances 100 substantially equal to their width, said corrugations merging adjacent the middle of the plate into a lesser number of deeper corrugations spaced apart distances substantially equal to their width. 105

6. A metallic plate provided with a plurality of corrugations symmetrical in cross section about a line midway between the outermost portions of the corrugations, said corrugations merging adjacent the middle 110 of the plate into a lesser number of wider and deeper corrugations symmetrical in cross section about a line midway between the outermost portions of the corrugations.

7. A metallic plate provided with a plurality of corrugations symmetrical in cross section about a line midway between the outermost portions of the corrugations, said corrugations merging adjacent the middle of the plate into a lesser number of deeper corrugations symmetrical in cross section about a line midway between the outermost portions of the corrugations. 115

8. A metallic plate provided with a plurality of shallow corrugations merging adjacent the middle of the plate into a lesser number of deeper corrugations, the length of the center line of the metal of a cross section of the shallower corrugations being substantially equal to the length of the center 125 130

line of the metal of a cross section of the deeper corrugations.

9. A metallic plate provided with a plurality of shallow corrugations merging adjacent the middle of the plate into a lesser number of wider and deeper corrugations, the length of the center line of the metal of a cross section of the shallower corrugations being substantially equal to the length of the center line of the metal of a cross section of the deeper corrugations.

10. A metallic plate provided with a plurality of corrugations of constant cross section for a short distance at the center of the plate which diverge into a greater number of shallower corrugations adjacent the edge of the plate.

11. A metallic plate provided with a plurality of corrugations merging adjacent the middle of the plate into a lesser number of wider and deeper corrugations, the length of the center line of the metal of any cross section of the corrugated plate being equal to the length of the center line of the metal of any other cross section.

12. A metallic plate provided with a plurality of corrugations merging adjacent the middle of the plate into a lesser number of deeper corrugations, the length of the center line of the metal of any cross section of the corrugated plate being equal to the length of the center line of the metal of any other cross section.

13. A metallic plate provided with a plurality of sinuous and contiguous corrugations, said corrugations merging adjacent the middle of the plate into a lesser number of deeper and wider corrugations with substantially flat apices.

14. A metallic plate provided with a plurality of sinuous and contiguous corrugations, said corrugations merging adjacent the middle of the plate into a lesser number of deeper corrugations with substantially flat apices.

15. A wall for a railway car comprising a metallic plate secured to oppositely disposed frame members of the car, said plate provided with a plurality of corrugations with their opposite ends terminating into the plate adjacent said oppositely disposed frame members, said corrugations merging together adjacent the middle of the plate to form a lesser number of deeper corrugations.

16. A wall for a railway car comprising a metallic plate secured to oppositely disposed frame members of the car, said plate provided with a plurality of corrugations with their opposite ends terminating into the plate adjacent said oppositely disposed frame members, said corrugations merging together adjacent the middle of the plate to form a lesser number of wider and deeper corrugations.

17. A wall for a railway car comprising a

metallic plate secured to oppositely disposed frame members of the car, said plate provided with a plurality of corrugations spaced apart distances substantially equal to their width with their opposite ends terminating into the plate adjacent said oppositely disposed frame members, said corrugations merging together adjacent the middle of the plate to form a lesser number of deeper corrugations spaced apart distances substantially equal to their width.

18. A wall for a railway car comprising a metallic plate secured to oppositely disposed frame members of the car, said plate provided with a plurality of corrugations spaced apart distances substantially equal to their width with their opposite ends terminating into the plate adjacent said oppositely disposed frame members, said corrugations merging together adjacent the middle of the plate to form a lesser number of wider and deeper corrugations spaced apart distances substantially equal to their width.

19. A wall for a railway car comprising a metallic plate secured to oppositely disposed frame members of the car, said plate provided with a plurality of corrugations symmetrical in cross section about a line midway between the outermost portions of the corrugations with their opposite ends terminating into the plate adjacent said oppositely disposed frame members, said corrugations merging together adjacent the middle of the plate to form a lesser number of deeper corrugations, symmetrical in cross section about a line midway between the outermost portions of the corrugations.

20. A wall for a railway car comprising a metallic plate secured to opposite disposed frame members of the car, said plates provided with a plurality of corrugations symmetrical in cross section about a line midway between the outermost portions of the corrugations with their opposite ends terminating into the plate adjacent said oppositely disposed frame members, said corrugations merging together adjacent the middle of the plate to form a lesser number of wider and deeper corrugations symmetrical in cross section about a line midway between the outermost portions of the corrugations.

21. A wall for a railway car comprising a metallic plate secured to oppositely disposed frame members of the car, said plate provided with a plurality of corrugations with their opposite ends terminating into the plate adjacent said oppositely disposed frame members, said corrugations merging together adjacent the middle of the plate to form a lesser number of wider and deeper corrugations, the length of the center line of the metal of a cross section of the shallower corrugations being substantially equal to the length of the center line of the metal

of a cross section of the deeper corrugations.

22. A wall for a railway car comprising a metallic plate secured to oppositely disposed frame members of the car, said plate provided with a plurality of corrugations with their opposite ends terminating into the plate adjacent said oppositely disposed frame members, said corrugations merging together adjacent the middle of the plate to form a lesser number of deeper corrugations which are of constant cross section for a short distance at the center of the plate.

23. A wall for a railway car comprising a metallic plate secured to oppositely disposed frame members of the car, said plate provided with a plurality of corrugations with their opposite ends terminating into the plate adjacent said oppositely disposed frame members, said corrugations merging together adjacent the middle of the plate to form a lesser number of wider and deeper corrugations which are of constant cross section for a short distance at the center of the plate.

24. A wall for a railway car comprising a metallic plate secured to oppositely disposed frame members of the car, said plate provided with a plurality of sinuous and contiguous corrugations with their opposite ends terminating into the plate adjacent said oppositely disposed frame members,

said corrugations merging together adjacent the middle of the plate to form a lesser number of deeper corrugations with substantially flat apices.

25. A wall for a railway car comprising a metallic plate secured to oppositely disposed frame members of the car, said plate provided with a plurality of sinuous and contiguous corrugations with their opposite ends terminating into the plate adjacent said oppositely disposed frame members, said corrugations merging together adjacent the middle of the plate to form a lesser number of wider and deeper corrugations with substantially flat apices.

26. A wall for a railway car comprising a metallic plate secured to oppositely disposed frame members of the car, said plate provided with a plurality of corrugations with their opposite ends terminating into the plate adjacent said oppositely disposed frame members, said corrugations merging together adjacent the middle of the plate to form a lesser number of deeper corrugations, the length of the center line of the metal of a cross section of the shallower corrugations being substantially equal to the length of the center line of the metal of a cross section of the deeper corrugations.

ARTHUR E. SMALL.
